DESIGN FOR A BOWL OR SIMILAR ARTICLE

John Rubel, New York, N. Y.

Application March 25, 1946, Serial No. 127,903

Term of patent 7 years

(CL. D44—15)

To all whom it may concern:

Be it known that I, John Rubel, a citizen of the Republic of France, residing in New York city, in the county of New York and State of New York, have invented a new, original, and ornamental Design for a Bowl or Similar Article, of which the following is a specification, reference being had to the accompanying drawing, forming part thereof.

Fig. 1 is a perspective view of a bowl, showing my new design, and

Fig. 2 is a top plan view thereof.

I claim:

The ornamental design for a bowl or similar article, substantially as shown.

JOHN RUBEL.
